UNITED STATES PATENT OFFICE.

JAMES W. TAYLOR, OF SAN ANTONIO, TEXAS.

PUMPING APPARATUS.

Application filed March 16, 1925. Serial No. 15,761.

To all whom it may concern:

Be it known that I, JAMES W. TAYLOR, a citizen of the United States, residing at San Antonio, in the county of Bexar and State 5 of Texas, have invented certain new and useful Improvements in Pumping Apparatus, of which the following is a specification.

This invention relates to an improved flowing or pumping apparatus for removing liquids from oil wells, the object of the invention, generally stated, is the provision of apparatus of this character which, when inserted within a well, will serve to force the liquid in the well to the surface by means of 10 the expansive power of the natural gas generated or contained within the well.

In accordance with the invention there is provided a pumping apparatus for the purpose set forth consisting broadly of a well 20 casing in which is positioned the centrally disposed flow line or tubing. This tubing carries, at a position near the lower part of the well, a flow hood in which the natural gas of the well is trapped, there being an entry between the hood and the flow line by 25 means of which the trapped expansible fluid is permitted to enter the flow line to effect the elevation of the liquid therein. The entry is provided with an associated valve 30 mechanism for controlling fluid flow therethrough, and the particular feature of the present invention resides in the provision of automatically operating means for controlling the operation of the valve mechanism, 35 wherein the arrangement is such that when the fluid pressure within the casing reaches a predetermined pressure, the valve mechanism will be open to permit the expelling fluid to enter the flow line and expand, and when the gas pressure in the casing is reduced to a predetermined pressure, the valve mechanism will be operated to close the entry and to arrest further liquid flow 40 through the flow line or tubing until the gas pressure has been again built up to a point permitting of the opening of the valve mechanism.

With these and other objects in view, as will appear as the description proceeds, the 50 invention consists in the novel features of construction, combinations of elements and arrangements of parts hereinafter to be fully described and pointed out in the appended claims:

In the accompanying drawing: Figure 1 is a vertical cross-sectional view

taken through the pumping apparatus situated at the upper end of a well casing,

Figure 2 is a vertical cross-sectional view 60 taken through the well casing, the tubing and flow hood, and showing the valve mechanism employed in controlling gas flow into the tubing.

Referring to the drawings, the numeral 1 65 designates a standard form of well casing which is adapted to be inserted into a drilled well opening and to extend from the surface of the well to the oil producing sands. Within the casing extending axially and longitudinally therethrough is a flow line or tubing 70 2 having a perforated lower end 3 which rests upon the bottom plug 4 provided in a well screen 5, the lower end of the screen 5 resting upon the bottom of the well. By this it will be seen that a standard construction 75 is provided, although other forms may be used, in which oil will be permitted to enter the flow line and to arise therein, as well as in the casing, by the natural pressure or flow of the oil or liquid, and that the height 80 which the oil will reach in the flow line and the casing will vary in accordance with the natural pressures existing in each well.

Applied to the upper end of the casing 1 is 85 a casing head 6, through which the upper end of the flow line extends and in which the flow line is suitably sealed, as will be hereinafter described, to confine within the casing the natural gases of the well for the purpose of employing these gases in the expelling of the liquid.

The flow line 2 in this instance includes 90 relatively movable upper and lower sections 7 and 8 respectively. The upper section is provided at its lower end with a threaded coupling 9, which supports a nozzle 10, constructed to restrict the diameter of the flow line to facilitate the liquid's expulsion. The lower end of the nozzle is threaded to receive the cap section 11 of a flow hood designated generally by the numeral 12.

The hood consists of a cylindrical casing 13, closed at its upper end and open at its lower end as indicated by the numeral 14. The diameter of the casing 13 is slightly less 105 than the internal diameter of the casing 1, so that fluid arising within the casing 1 is circulated around the hood and into the upper part of the casing 1 above the flow hood. The casing 13 may be of any suitable 110 length and formed sectionally, as shown in Figure 2, the sections thereof being united

by one or more internal couplings 15. It will be seen that by this construction the natural gas delivered from the well will accumulate in part in the upper closed end of 5 the hood and will be prevented from expanding while retained within the hood, by reason of the fluid pressure contained within the casing 1 above the hood.

In order to admit the gas into the flow 10 line to expel the liquid therein, there is provided a valve mechanism which in this instance consists of a sleeve 16, provided with an annular enlargement 17 having rounded upper and lower shoulders 18 and 19. These 15 shoulders are adapted for engagement with beveled upper and lower seats 20 and 21 respectively, the former of which being provided at the lower end of the cap section 11, while the latter is provided internally with 20 in a tube 22 threadably connected with the cap section 11 at 23. The lower end of the tube 22 has an opening provided therein for the sliding reception of the sleeve 16, and said opening possesses a greater diameter 25 than the external diameter of said sleeve at this point so as to permit of fluid passage through the interior of said tube. The open end of the sleeve 16 is provided with a plurality of passages or entries 24, and it will 30 be seen that when the enlargement 17 is positioned mid-way in the length of the tube 22, or in other words, when the shoulders 18 and 19 are spaced from the seats 20 and 21, fluid will be permitted to flow from beneath 35 the hood, through the tube 22 and thence by way of the passages 24 into the liquid contained within the flow line.

It will be understood that the fluid pressures within the flow line and within the 40 casing 1 or the hood 12 are substantially equalized or balanced adjacent the passages 24, so that a slight excess of pressure in the casing 1 or within the flow hood 12 will be sufficient to force or permit the expelling 45 gas to enter the flow line against the resistance offered by the hydro-static head of the column of liquid in the flow line.

Since the gas is maintained in its normal compressed state within the hood by the fluid 50 pressure above the same, it follows that when this gas enters the flow line, that the liquid pressure in the latter prevents immediate expansion of the gas. In other words, the gas will enter the flow line in small 55 bubbles which by virtue of their natural buoyancy will arise vertically through the liquid in the flow line and will expand so as to become gradually enlarged as the bubbles ascend the flow line. This expansion, of 60 course, becomes greater when the hydro-static pressure thereon is gradually diminished by the rise thereof in the column of liquid, since as the bubbles near the top of the flow line the liquid pressure becomes correspondingly smaller. The bubbles are then

permitted to expand to their maximum point wherein they substantially fill the tubing and therefore serve in the capacity of pneumatic pistons for expelling the liquid at the top of the flow line. The bubbles follow 70 one another in very rapid succession at accelerated speed of travel and consequently can expel a large volume of liquid from the tubing.

Since the apparatus described relies upon 75 the natural gas pressure in the well to expel the liquid, it follows that in most wells this pressure can not be generated sufficiently to provide for a continuous flowing of the well, and therefore it is necessary to provide 80 for an intermittent opening and closing of the valve mechanism so that the pressure of the gas may be built up and released in "heads" or impulses for the purpose of expelling the fluid. It is a primary object 85 of the present invention to automatically regulate the opening and closing of the valve mechanism, in contrast to the manually operated structure, disclosed in my co-pending application filed March 16, 1925 Serial Number 15,760. Since the lower section 8 of the tubing rests upon the bottom of the well, I provide a structure by means of which the upper section of the flow line together with the hood may be raised and lowered at intervals 90 so as to cover and uncover the ports or passages 24.

The structure for accomplishing this object is disclosed in Figure 1 and consists of a cylinder 25 formed with the casing head 1. Mounted within the cylinder is a piston 6. Mounted within the cylinder is a piston which consists of a base section 26 and a top section 27, the base section having its periphery provided with an annular shoulder 28, while the top section is provided with a depending annular flange 29 arranged to engage with the upper surface of the ring 28. The base section is provided with a plurality of upstanding stud bolts 30 upon the upper ends of which are threaded binding devices for the purpose of forcing the top section downwardly and expanding the ring 28 into firm sealing engagement with the inner wall of the cylinder 25. The base section 26 is also provided adjacent the axial portion thereof with a shoulder 31, upon which seats a packing ring 32, which engages with the outer surface of the flow line 2. Threadedly carried by the base section 1 of the piston is an upstanding tube 33 having its upper end projected through the sectional cover 34 of the cylinder and provided with a seat upon which rests a thrust bearing 35. The flow line at this point is provided with raised threads 36 adapted for the reception of the threaded hub of an adjusting wheel 37, which is employed to limit the downward movement of the upper section 7 of the flow line and thereby controls 1

the extent of the opening and closing movement of the valve mechanism. The flow line, beneath the packing 32 is provided with a fixed collar 38 upon which rests a gasket 39, 5 the latter being arranged to open and close a passage 40 leading from the top of the casing 1 into the under part of the cylinder 25.

The casing head 6 carries an upstanding frame 41 formed of joined pipe sections and fittings which comprise a support for the upper part of the flow line above the cylinder 25. This frame also includes a conduit 42 controlled by a valve 43 by means of 10 which gas pressure in the casing may be relieved when desired. The upper end of the frame 41 includes a guide 44 in which the flow line is slidably received. This guide at its lower end is provided with a packing 15 45 preventing the escape of the fluid from the upper part of the flow line. Above the packing 45 is provided a stationary outlet conduit 46 which leads the liquid from the well to a suitable point of discharge.

25 In operation, it will be seen that, after the casing has been inserted in the well, the flow line is dropped vertically until its lower end rests upon a stationary abutment, in this instance the screen 5. As the flow line is being lowered the shoulder 19 will engage with the seat 21 so as to close the upper end of the chamber 47 formed under the hood 12, so that the gas which accumulates within the hood will be trapped and reserved for subsequent use. When the flow line has been 30 finally positioned within the casing the natural fluid pressure in the well is permitted to build up in the casing 1 and in the chamber 47, this being accomplished by the sealing of the open end of the casing. When 35 this fluid pressure reaches a predetermined point necessary to effect the flowing of the well, it will be seen that the pressure exercised on the under side of the piston in the cylinder 25, will be sufficient to effect the elevation of said piston, which in turn by reason of its connection with the flow line, raises the upper section 7 of said flow line so as to uncover the ports 24. This 40 allows the gas in the chamber 47, which has been maintained under pressure, to flow through said ports, as previously described, into the flow line and effect the elevation of liquid. As the gas is displaced in the hood, 45 it follows that there is a receding in level of the liquid in the casing above the hood, which results in the expansion of the gas in the upper part of the casing 1, thus reducing the pressure on the piston in the cylinder 25 so that the latter will return to a 50 lowered position and thereby dropping the flow line to close the valve mechanism as shown in Figure 2. The closing of the valve mechanism arrests further fluid flow into the tubing 2, and permits the well to again

build up sufficient pressure to effect the raising of the piston.

By controlling the friction which the ring 28 exercises on the inner wall of the cylinder 25, the operation of said piston, in responding to the fluctuating gas pressures, may be controlled so that there will be an appreciable interval wherein the gas is permitted to enter the tubing from the flow hood and another appreciable interval wherein gas 70 flow is prevented. This will result in the production of the gas heads used in flowing the well intermittently and insures complete opening and closing on the part of the valve mechanism. It will thus be seen that the present invention provides means for flowing a well by the natural gas pressure of said well, and that the operation thereof is rendered entirely automatic and manual control and supervision reduced to a minimum. This feature is particularly important in large oil fields and in the flowing of small capacity wells wherein it is not practicable or economical to have constant 80 manual supervision.

90 What is claimed is:

1. In oil well pumping apparatus, a casing, a flow line in said casing, a hood surrounding said flow line open at its lower end and normally closed at its upper end, a valve mechanism establishing communication between the closed portion of said hood and said flow line, and means operated automatically by natural gas pressure stored within said casing for effecting the operation of said valve mechanism.

95 2. In pumping apparatus, a well casing, a flow line in said casing, a hood in said casing surrounding said flow line, said hood being provided with a substantially opened lower end and closed upper end providing a chamber between the walls of said hood and flow line for the trapping of gas arising within the well, a valve mechanism for governing fluid flow between said chamber 100 and flow line, a closed reservoir in the casing above said hood, and means operable by the expansion and contraction of the fluid in said reservoir to open and close said valve mechanism.

110 3. In pumping apparatus, a well casing, a flow line extending through said casing, a hood in said casing and surrounding said flow line at a suitable point of its length, said hood serving to trap therein the natural gas arising in said well, a valve mechanism to permit said gas to enter the flow line to expel the liquid therein, a closed head provided upon the upper end of said casing and a pressure operated device responsive to fluctuating pressures in said head to operate said valve mechanism.

120 4. In pumping apparatus, a well casing, a tubing extending through said casing, a flow head carried by said tubing and serving to 125

- trap therein natural gas rising in the well, valve mechanism for governing the flow of gas from said hood into said tubing, a head provided on the upper end of said casing, a piston mounted within said head and responsive to fluid pressures therein, and operating devices between said piston and said valve mechanism for controlling the operating positions of the latter.
5. In pumping apparatus, a well casing, a tubing extending through said casing, a flow hood, valve mechanism between said flow hood and tubing, a cylinder in communication with the upper end of said casing, a piston in said cylinder, and connections between said piston and tubing, said tubing serving upon movement on the part thereof in unison with said piston to regulate the opening and closing of the valve mechanism.
6. In pumping apparatus, a well casing, a tubing positioned within said casing and including relatively movable upper and lower sections, a flow hood surrounding said tubing, valve mechanism at the junction of said tubing sections for governing fluid flow from said hood into said tubing, a head provided at the upper end of said casing, a piston in said head adapted to be raised and lowered by fluctuating fluid pressures in said
- 10 5. In pumping apparatus, a well casing, a tubing constituting a flow line provided in said casing, said tubing including relatively movable upper and lower sections, a flow 40 hood surrounding said tubing, a valve mechanism situated at the point of junction of the upper and lower sections of said tubing and serving to control fluid flow between said hood and said tubing, a head arranged to seal the upper end of said casing, a piston working in a cylinder provided in said head and adapted to be raised and lowered by varying fluid pressures in the casing above said hood, means connecting the upper section of said tubing with said piston, whereby upon movement of the latter said upper section of the tubing will be operated to open and close said valve mechanism, and means for controlling the extent of movement of the upper section of said tubing.
- 15 45 5. In pumping apparatus, a well casing, a tubing constituting a flow line provided in said casing, said tubing including relatively movable upper and lower sections, a flow 50 hood surrounding said tubing, a valve mechanism situated at the point of junction of the upper and lower sections of said tubing and serving to control fluid flow between said hood and said tubing, a head arranged to seal the upper end of said casing, a piston working in a cylinder provided in said head and adapted to be raised and lowered by varying fluid pressures in the casing above said hood, means connecting the upper section of said tubing with said piston, whereby upon movement of the latter said upper section of the tubing will be operated to open and close said valve mechanism, and means for controlling the extent of movement of the upper section of said tubing.
- 20 55 5. In pumping apparatus, a well casing, a tubing constituting a flow line provided in said casing, said tubing including relatively movable upper and lower sections, a flow hood surrounding said tubing, a valve mechanism situated at the point of junction of the upper and lower sections of said tubing and serving to control fluid flow between said hood and said tubing, a head arranged to seal the upper end of said casing, a piston working in a cylinder provided in said head and adapted to be raised and lowered by varying fluid pressures in the casing above said hood, means connecting the upper section of said tubing with said piston, whereby upon movement of the latter said upper section of the tubing will be operated to open and close said valve mechanism, and means for controlling the extent of movement of the upper section of said tubing.
- 25 5. In pumping apparatus, a well casing, a tubing constituting a flow line provided in said casing, said tubing including relatively movable upper and lower sections, a flow 55 hood surrounding said tubing, a valve mechanism situated at the point of junction of the upper and lower sections of said tubing and serving to control fluid flow between said hood and said tubing, a head arranged to seal the upper end of said casing, a piston working in a cylinder provided in said head and adapted to be raised and lowered by varying fluid pressures in the casing above said hood, means connecting the upper section of said tubing with said piston, whereby upon movement of the latter said upper section of the tubing will be operated to open and close said valve mechanism, and means for controlling the extent of movement of the upper section of said tubing.
- 30 5. In pumping apparatus, a well casing, a tubing constituting a flow line provided in said casing, said tubing including relatively movable upper and lower sections, a flow hood surrounding said tubing, a valve mechanism situated at the point of junction of the upper and lower sections of said tubing and serving to control fluid flow between said hood and said tubing, a head arranged to seal the upper end of said casing, a piston working in a cylinder provided in said head and adapted to be raised and lowered by varying fluid pressures in the casing above said hood, means connecting the upper section of said tubing with said piston, whereby upon movement of the latter said upper section of the tubing will be operated to open and close said valve mechanism, and means for controlling the extent of movement of the upper section of said tubing.

In testimony whereof I affix my signature.

JAMES W. TAYLOR.
